CARTON

Milton A. Smith, Chicago, Ill., assignor to Chicago
Carton Company, Chicago, Ill., a corporation
of Delaware

Application August 12, 1940, Serial No. 352,213

3 Claims. (CL 229—17)

This invention relates to an improvement in cartons and more particularly to paper board cartons. The main objects of the invention are to provide a carton of the character indicated with a dispensing spout; to provide a dispensing spout in a carton which may be easily and repeatedly opened and closed; to provide a dispensing spout construction which is contained wholly within the thickness of a wall structure of a carton and is free from any part projecting into the interior of the carton; to provide an arrangement whereby the movement of the spout from closed to open position and from open position to closed position is effectively limited; to provide a dispensing spout construction having the indicated characteristics which will be efficient and durable in use and which may be easily and economically manufactured; and in general, it is the object of the invention to provide an improved dispensing spout structure for cartons.

Other objects and advantages of the invention will be understood by reference to the following specification and accompanying drawings (two sheets) wherein there is disclosed a carton embodying a selected form of the improved spout construction.

In the drawings:

Fig. 1 is a perspective of a carton in closed, sealed condition and which is provided with the improved dispensing spout structure;

Fig. 2 is a perspective of an end portion of the carton provided with the improved spout and shown in opened position;

Fig. 3 is a section on the line 3—3 of Fig. 2;

Fig. 4 is a section on the line 4—4 of Fig. 3;

Fig. 5 is a plan of the spout containing end of the carton with one flap portion removed to more clearly reveal the construction of the spout;

Fig. 6 is a perspective of the carton in partially formed condition and showing the formation of the spout structure in the flaps for closing one end of the carton; and

Fig. 7 is a plan of the blank from which the carton is formed.

Referring now to the drawings, the dispensing spout construction herein contemplated is illustrated in connection with a conventional form of rectangular carton formed from a blank such as illustrated in Figure 7. Said blank is provided with suitable fold lines indicated at 8 which facilitates folding of the carton to form a tubular body, one end of the blank being provided with a lip or flap 9 adapted to be secured in overlapping relation to a corresponding marginal portion of

the opposite end of the blank. The blank is also provided with suitable fold lines 10—10 which facilitate folding of end forming flaps to form multi-ply end walls for the carton body. In this instance the bottom of the carton is formed by flaps 11 separated by slits 12, the flaps being folded into overlapping relation in any suitable manner as indicated in Figures 3 and 4 and stapled or adhesively or otherwise secured in such position.

The top end closure is similarly formed by means of flaps 13, 14, 15 and 16 which are foldable into overlapping relation along the upper fold line 10. The side wall flaps 13 and 15 are adapted to be first folded inwardly and they may be of such length that their inner edges will meet intermediate the width of the carton, or they may overlap somewhat as indicated in Figure 3. Said flaps are, however, provided with notches or openings such as indicated at 17 so as to provide an outlet opening through said flaps 13 and 15 when in end wall forming position.

The end flap 16 is next folded inwardly into overlapping relation to the flaps 13 and 15. The flap 16 may be adhesively secured to the underlying flaps 13 and 15 by adhesive applied so as to contact marginal portions of the flap 16 as indicated at 18 in Figure 7. Said flap is provided within its periphery with spout forming structure comprising a spout bottom wall portion 19, segmental side wall portions 20, 20 and movement limiting wings 21, 21. The spout forming structure is separated from the flap 16 by slitting 22 except that it remains integrally but hingedly connected to the flap along a fold line indicated at 23. The flap is further provided with cut-outs or openings 24, 24 in which the said wings 21, 21 are adapted to travel incident to opening and closing of the spout.

The side wall portions 20, 20 are foldable relative to the bottom wall portion 19 along suitably formed fold lines 25, 25 and said side wall portions are foldable relative to the wings 21, 21 or suitable fold lines 26, 26. The end walls 20, 20 are also bendable along suitable fold lines 27, 27.

After the end flap 16 is folded and adhesively secured to the underlying flaps 13 and 15 the end flap 14 is folded into overlapping relation to said flap 16. The flap 14 is also adhesively secured in position by means of adhesive which will contact only the marginal portion of the flap as indicated at 28 so as to avoid any adhesive connection between the flap 14 and any portion of the spout forming structure of the flap 16. The flap 14 is provided with perforated

score lines indicated at 29 and a short slit 30 which define a removable central portion through which the spout structure is adapted to be withdrawn when said removable portion is torn out of the flap 14. The slit 30 serves to provide access to the removable portion of the flap 14 to facilitate removal thereof.

The completed package appears as shown in Figure 1 with a removable portion visible on the top end wall flap 14, said removable portion being, however, effectively retained in the flap 14 until it is positively and intentionally torn out. As soon as the removable portion 31 is torn out, there is exposed in the opening so formed the bottom wall portion 19 of the spout structure, the hinge line 23 of which is substantially coincident with one edge of the opening in the flap 14. The opposite or slit formed end of the spout bottom 19 is preferably arched as illustrated and approaches the adjacent side of said opening in the wall 14 and it will be observed that the outward recess formed by the slit 30 facilitates access to said slit formed end 19 of the spout structure.

It will be observed that the spout structure is confined between the innermost flaps 13 and 15 and the outer flap 14 and within the thickness of the flap 16, in which the spout structure is formed. Inasmuch as the adhesive employed for securing the overlying flaps in closed position are restricted to marginal portions of the flaps, the spout structure remains free except for its hinge connection to the flap 16, so that the bottom wall portion 19 of the spout may be pulled outwardly with the result that the side portions 20, 20 will be withdrawn from between the flaps 13 and 14 or 15 and 14, to the extent permitted by the openings 24, 24 and the wings 21, 21. It will be observed that the wings 21, 21 are confined between the flaps 13 and 14 or 15 and 14, for lateral movement, and that such movement of the wings is restricted by the length of the opening 24. Outward or opening movement of the spout is of course stopped by engagement of the front edges 32, 32 of the wings with the ends 33, 33 of said openings 24. Closing movement of the spout structure is limited by engagement of the edges 34, 34 of the wings with the adjacent edges of the flap 16.

In the opening and closing movement of the spout structure, the side forming portions 20, 20 thereof bend upon themselves along the fold lines 27, such bending facilitating the withdrawal and return of said wings from between the respective underlying and overlying flaps.

The described dispensing spout structure involves no extra forming operations, nor any extra parts. The various slits and fold lines required for production of the spout structure may be produced in connection with the normal box blank cutting operations and the structure is such that conventional box forming equipment may be employed for setting up the boxes. Hence the structure is both easy and economical to produce. Changes in the structure may be made without departing from the spirit of the invention, the scope of which should be determined by reference to the following claims, the same being construed as broadly as possible consistent with the state of the art.

I claim:

1. A paper board container having a wall comprising inner, outer and intermediate portions, said intermediate portion being cut and scored so as to define a pouring spout structure having

a bottom hingedly connected to said intermediate wall portion and sides foldably connected to said bottom, said spout structure being free of face to face attachment to said inner and outer walls and being adjustable from closed position substantially co-planar with said intermediate wall portion to open position wherein said spout bottom is swung outwardly on its hinged connection with the intermediate wall and said spout sides are moved edgewise from said closed position between said inner and outer wall portions to angularly, outwardly extending position relative to said wall of the container, said inner and outer wall portions having openings registering with said spout bottom for the discharge of the content of the container from said spout, the opening in said outer wall portion also serving to permit opening of the spout structure as aforesaid, and means for limiting the opening movement of said spout structure, said means comprising an edgewise extension on one of said spout sides and a recess in said intermediate wall portion for movably receiving said extension, said recess and extension being so arranged and being of such size as to limit the movability of said extension.

2. In a paper board container of the class described, a wall comprising inner, outer and intermediate overlapping portions, a spout structure in said intermediate portion comprising a bottom, sides and wing portions extending beyond said sides, said spout structure being foldably connected to said intermediate wall portion along one end of said bottom but being elsewhere separated from said intermediate wall portion, said inner and outer wall portions being provided with dispensing openings substantially registered with said spout bottom so as to permit outward folding of said spout bottom in the opening of said outer wall portion, said spout sides being thereby incidentally movable edgewise from between said inner and outer wall portions and said intermediate wall portion being provided with openings for permitting limited edgewise movement of said wings within the thickness of said intermediate wall as an incident to said movement of the spout sides, said last mentioned openings respectively having edge portions spaced from edge portions of said wings when the spout is closed and said opening edge portions being adapted to be engaged by said wing edge portions to limit the outward folding of said spout bottom and sides to a predetermined dispensing spout-forming position.

3. A paper board container having a wall comprising mutually overlapping inner, outer and intermediate portions, said intermediate portion being cut and scored so as to provide a foldable spout structure embodying a spout bottom hingedly connected at one end to said intermediate wall portion, spout sides each embodying a pair of hingedly connected sections, a pair of wings, one of said side sections of each pair being hingedly connected to a side edge of said spout bottom and the other side section of each pair being hingedly connected to one of said wings, said wings projecting beyond the end edges of the respective sections, said spout structure having a normally closed position, co-planar with said intermediate wall portion and being adjustable to open position by outward swinging of said spout bottom on its hinge connection with said intermediate wall portion together with incidental edgewise movement of

said side sections from between said inner and outer wall portions to open spout-side position, said intermediate wall portion being provided with openings permitting limited edgewise movement of said wings within the thickness of said intermediate wall as an incident to said movement of the side sections, said openings and wings having edge portions adapted to interengage to limit opening movement of said wings to thereby limit the opening movement of the spout structure, the hinged connection between the sections of each spout side serving in the closing

of the spout to facilitate initial movement of the innermost section to approximately coplanar relation to said intermediate wall to thereby facilitate lateral movement of said innermost section inwardly between the inner and outer wall portions, and said inner and outer wall portions being provided with openings substantially registering with said spout bottom to permit opening of said spout structure as aforesaid and for the discharge of material from the container over said spout.

MILTON A. SMITH.
